LAUNDRY TUB MOLD

Joseph B. Ryan, Chicago, Ill., assignor of one-half to Robert S. Grogan, Chicago, Ill.

Application May 5, 1934, Serial No. 724,012

5 Claims. (Cl. 25—130)

This invention relates to the art of molding appliances, and has reference more particularly to molds used in the manufacture of modern monolithic laundry tubs. Owing to the shape of these tubs, which are usually made with a downwardly and rearwardly inclined front wall, it is necessary to build the mold in separable parts in order to effect the removal of the molded structure after the poured cementitious material has set and hardened, and these parts have heretofore, so far as I am aware, been fastened together by bolts, the application and removal of which involves considerable time and labor. One object of the present invention has been to provide a mold of this type in which the use of bolts and similar fastening devices may be dispensed with and replaced by other fastening devices in the nature of clamps which can be quickly and easily applied and removed.

Monolithic laundry tubs are now made with a metal wash board permanently embedded in the inner surface of the sloping front wall of the tub. Heretofore considerable difficulty has been experienced in providing reliable supporting means for the wash board in the mold that will securely hold the board in fixed position during the pouring operation and prevent its accidental displacement which, of course, renders the product imperfect and unsaleable. Another object of the invention has been to provide a simple and reliable wash board support for the mold that will securely hold the wash board in its true position during the pouring and that can be easily removed after the material has set.

Other objects and attendant advantages of the invention will be apparent to persons skilled in the art to which the invention belongs from the following description, taken in connection with the accompanying drawings, which illustrate one practical and approved embodiment of the invention, and wherein—

Fig. 1 is an end elevation of the mold.

Fig. 2 is a front elevation, viewed from the right of Fig. 1 and broken out between its ends.

Fig. 3 is a perspective view of the bottom or base member of the mold.

Fig. 4 is a perspective view of one of the twin members which determine the form and size of the internal walls of the washing compartments of the tub.

Fig. 5 is a vertical transverse section on the line 5—5 of Fig. 2.

Fig. 6 is a view similar to Fig. 5, but showing the separable members of the complete mold

spaced apart to more clearly show the structural features of said members.

Fig. 7 is a vertical longitudinal section, broken out between its ends, on the line 7—7 of Fig. 1, but with the inner mold members left in elevation to show the manner of supporting a metal washboard to be embedded in the front wall of the tub, the front wall of the left hand mold member being broken away to disclose in part the rear wall thereof.

Fig. 8 is a perspective group view, showing the two inner mold members mounted on the base, and the other parts spaced therefrom.

Fig. 9 is an enlarged fragmentary perspective view of an upper end portion of the assembled mold, showing the interfitting relation of an end wall with the rear and front walls.

Fig. 10 is a detail sectional view showing an automatic lock for the two locking bars that hold the front, rear and end walls of the mold in assembled relation.

Proceeding now to a detailed description of the mold structure as illustrated in the drawings, and referring first to the group view, Fig. 8, the principal concrete shaping parts consist of a bottom or base member A, a front wall member B, a rear wall member C, duplicate end wall members D, and twin inner or compartment forming members E. The front, rear and end walls are clamped together by a pair of locking bars designated as a whole by F, and the base is secured to the front and rear walls by locking devices designated as a whole by G.

The bottom or base member A, shown in isolated detail in Fig. 3, comprises a rectangular angle bar frame 11, supplied with transverse T-bars 12, angles 13 lying against the inner sides of the end members of frame 11, and angle sections 14 lying against the inner side of the front member of frame 11 between the T-bars 12. As shown in Figs. 3 and 7, the tops of the bars 12, 13 and 14 are slightly below the top of the main frame 11, and these bars form a seat for the front and end walls of the two hollow inner mold members E. Overlying the rear portion of frame 11 and secured thereto and spaced therefrom by a pair of bars 15 and 16 (Figs. 5 and 6) is a longitudinally extending plate 17 that molds a countersunk seat in a shelf on the rear top edge of the tub. This plate 17 is formed on its inner edge with a low upstanding flange 18 that forms a line joint with the shortened rear wall 19 of the inner mold members E, as clearly shown in Fig. 5. Said rear wall 19 is preferably stiffened by a transverse angle-bar 20, the vertical limb

of which overlaps the joint and aids in accurately positioning the mold E on the base A. On the upper surface of the plate 17 are a pair of grids 21 in relief which mold soap dishes or holders 5 in the seat of the shelf, and also a pair of pins 22 which mold holes in the shelf for bolts that fasten a faucet fixture to the shelf. The pins 22 are loosely mounted in the plate 17 so that, when the mold is dismantled after the material has 10 set, these pins remain in the shelf and may be individually removed, thereby avoiding chipping at the holes formed by the pins.

The vertical rear wall C, fabricated as shown in Figs. 5, 6 and 8, is formed with a downwardly 15 and rearwardly curved lower end portion 23 that is spaced from the plate 21 by an underlying bar 24 and vertical transverse end plates 25 resting on the base frame 11; these parts 23, 24 and 25 cooperating with the plate 17 to mold the 20 shelf on the upper edge of the rear wall of the tub. The inner face of the strip 25 makes a joint with the rear vertical edge of the end wall D, as shown at 26 in Figs. 5 and 9, and the end wall is locked against outward movement by an 25 angle bar 27 secured to the inner face of the plates 25 and a corresponding angle bar on the front wall B later described.

The inclined front wall B of the mold is fabricated in the same manner as the rear wall C, except that it is flat throughout with its lower edge 30 resting on the frame 11 and held against slip by chocks 28. On the inner face of wall B are plates 29, the inner face of each of which makes a joint with the front inclined edge of the end wall D, as shown at 30 in Figs. 5 and 9, and secured to the inner face of the plate 29 is an angle 35 bar 31 that cooperates with the angle bar 27 in locking the end wall against outward movement.

The form and structure of the end walls D are 40 clearly shown in Fig. 8, each wall being stiffened by top and bottom angles 32 and 33 and a vertical angle 34 on its outer side, the bottom horizontal edge of each wall D resting on the frame 11, as shown in Fig. 7.

The form and structure of each of the inner 45 or compartment-forming mold members E is clearly shown in Figs. 4 and 8 and in the sectioned views Figs. 5, 6 and 7. Their lower front and end edges rest on the frame bars 12 and 13, 50 and on their tops are lugs 35 for molding the usual drain holes in the bottom walls of the tub compartments.

Referring now to the means for supporting a metal wash board in the mold, so that it will be 55 embedded in the inner surface of the inclined front wall of the tub, 36 designates the wash board, the ribbed surface of which is bordered by a narrow rectangular marginal frame 37. Holes 39 (Fig. 8) are formed through the front 60 wall member B and to give greater depth to the holes 39, said holes are preferably also extended through flat strips 40 (Fig. 2) secured on the outer face of the wall B. Through the holes 39 are passed pins 41, the inner ends of said pins 65 engaging the board just inside the corners of its marginal frame 37, and preferably also between the corners, as shown in Fig. 7, and thus securely holding the board against displacement from its position of rest on the opposed inclined 70 wall of the mold member E, as shown in Fig. 5. To lock the pins in place, leaf springs 42 are pivoted on the strips 40, the free ends of which 75 overlie the outer ends of the pins. The pins are long enough to project slightly above the strips 40, as shown in Fig. 5, so that, after the ma-

terial of the tub has been poured and has only partly hardened, the springs 42 may be swung to one side, as shown in dotted lines in Fig. 2, and by a pair of pincers the pins can be withdrawn.

In one type of twin-compartment laundry tub 5 the top edge of the central transverse partition is slightly below the plane of the top edges of the front and side walls. When molding such a tub I provide for the shortening of the height of the partition by a bar 43 (Figs. 3 and 7) soldered 10 on or otherwise secured to the central T-bar 12 of the base frame.

Referring now to the means for locking together the separable parts of the mold, preliminary to the pouring operation, and first describing the means F by which the front, rear and side walls are securely bonded together, 44 designates each of a pair of clamp bars that, as shown in Fig. 1, extend across the outer sides of the end walls approximately mid-height of the latter. 20 The bar 44 is formed with an inwardly turned rear end portion 45 apertured to engage with a pin 46 on the rear side of the rear wall. 47 designates a keeper mounted on the vertical angle bar 34, which confines the bar 44 against lateral 25 displacement. The front end of the bar 44 is formed as a handle 48, and pivoted in a slot in the shank of the handle (Fig. 10) is a latch 49 formed with a curved serrated inner end 50 adapted to bitingly engage with a cam block 51 30 mounted on the outer side of the front wall member B. As the bar 44 is swung downwardly, the serrated edge 50 of the latch 49 rides over the outer curved face of the cam 51, being urged into locking engagement with the latter by an under- 35 lying spring 52. When it is desired to release the locking bar 44, after the mold has been poured and its contents set, this is easily done by merely pressing down with the thumb latch 49 so as to release it from biting engagement with the 40 cam 51, whereupon the bar 44 may be raised clear of the keeper 47, and then removed from the pin 46. It is understood, of course, that the hole engaged by the pin 46 is sufficiently larger than the pin to permit this swinging movement 45 of the bar 44.

Describing next the means G for locking the bottom frame member 11 to the lower ends of the front and rear walls, which means are best shown in Figs. 1, 2, 5 and 6, 53 designates each 50 of a pair of hooks, each of which is pivoted at 54 to the lower end of a short link 55 in turn pivoted to a lug 56 on the under side of the front member of the frame 11. The hook 53 may be readily swung upwardly to bring its free end into 55 engagement with a block 57 mounted on a longitudinal angle bar 58 on the lower edge of the front wall. The free end of the hook 53 is drawn into tight clamping engagement with the block 57 by means of a cam lever 59 pivoted at 60 on the hook 60 53 with its upper tapered end engaged with the horizontal flange of the frame 11, in a manner clearly shown in Fig. 1. Manifestly, by pressing the depending end of the cam lever 59 outwardly, the hook 53 is drawn downwardly and thus the 65 frame member 11 is tightly clamped against the lower edges of the walls of the mold.

The same mechanism is employed to lock the bottom frame member 11 to the lower end of the rear wall of the mold, and the parts of said mechanism are therefore identified by the same reference characters employed to designate the parts of the front mechanism.

In disassembling the parts of the mold to free the molded structure, all that is necessary to 75

free the base member is to push the depending ends of the cam levers 59 inwardly and then swing the hooks 53 clear of the front and rear walls, the hooks then occupying the suspended 5 positions partially illustrated in Fig. 6.

It will thus be apparent that the described mold requires no bolts, screws, or like fastening devices in order to assemble its parts, and this means a very considerable saving of time and labor in 10 preparing the mold for the pouring operation. It will also be apparent that the described means for supporting the wash board 36 during the pouring operation is not only extremely simple, but makes impossible any bodily or angular movement 15 of the wash board while the liquid material is being poured therearound. The frame 37 of the wash board lies snugly against the sloping wall of the inner mold member E, and this prevents the liquid material from flowing into or 20 over the ribbed or corrugated metal face of the wash board.

While I have herein shown and described a practical and preferred embodiment of the invention, I do not limit the latter to the specific 25 structural features set forth, but reserve all such variations, modifications and mechanical equivalents as fall within the spirit and purview of the claims.

I claim:

30 1. In a laundry tub mold, removable means for holding a wash board in position to be embedded in the inner surface of a wall of the tub, comprising a plurality of pins extending through holes in a wall of the mold with their inner ends 35 supportingly engaged with the wash board, and means for locking said pins in place during the molding operation.

2. In a laundry tub mold, removable means for holding a wash board in position to be embedded 40 in the inner surface of a wall of the tub, comprising a plurality of pins extending through holes in a wall of the mold with their inner ends

supportingly engaged with the wash board, and means on said mold wall movable into and out of engagement with the outer ends of said pins to lock the latter in place during the molding operation and permit their subsequent withdrawal. 5

3. In a laundry tub mold, removable means for holding a wash board in position to be embedded in the inner surface of a wall of the tub, comprising a plurality of pins extending through holes in a wall of the mold with their inner ends supportingly engaged with the wash board, and pivoted keepers on the outer side of said mold wall movable onto and off the outer ends of said pins to lock the latter in place during the molding operation and permit their subsequent withdrawal. 10 15

4. In a laundry tub mold having a front wall provided with fixed cams on its end portions, end walls, and a rear wall carrying rearwardly projecting pins on its end portions, means for holding said walls in assembled position, comprising clamp bars adapted to extend across said end walls and having laterally extending apertured end portions adapted to pivot on said pins, handles on and rigid with the forward portions 20 25 of said clamp bars, and gripping members on said handles adapted to have biting engagement with said cams.

5. In a laundry tub mold having a front wall provided with fixed cams on its end portions, end 30 walls, and a rear wall carrying rearwardly projecting pins on its end portions, means for holding said walls in assembled position, comprising clamp bars adapted to extend across said end walls and having laterally extending apertured 35 end portions adapted to pivot on said pins, handles on and rigid with the forward portions of said clamp bars, and latches pivoted on said handles and each formed with a curved serrated inner end adapted to bitingly engage with one 40 of said cams.

JOSEPH B. RYAN.
